CLAIM

The ornamental design for aroma diffuser set, substantially as shown and described.

DESCRIPTION

FIG. 1 is a front perspective view of an aroma diffuser set shown fully assembled;

FIG. 2 is a front perspective view of front of the body of the aromas diffuser set without the bottle;

FIG. 3 is a rear perspective view thereof;

FIG. 4 is a front view thereof;

FIG. 5 is a rear view thereof;

FIG. 6 is a left side view thereof;

FIG. 7 is a ride side view thereof;

FIG. 8 is a top view thereof;

FIG. 9 is a bottom view thereof;

FIG. 10 is an enlarged view of the detail area of FIG. 2 thereof;

FIG. 11 is an enlarged view of the detail area of FIG. 4 thereof;

FIG. 12 is a front perspective view of the bottle;

FIG. 13 is a rear perspective view thereof;

FIG. 14 is a front view thereof;

FIG. 15 is a rear view thereof;

FIG. 16 a left side view thereof;

FIG. 17 is a right side view thereof;

FIG. 18 is a top view thereof; and,

FIG. 19 is a bottom view thereof.

The evenly spaced broken lines depict portions of the aroma diffuser set that form no part of the claimed design. The dot dash dot broken lines denote the boundaries of the detail areas and from no part of the claim thereof.

The body of the aroma diffuser and the bottle are shown separately for convenience of illustration.
